UNITED STATES PATENT OFFICE

2,024,029

CONTAINER

Henry M. Dillhoefer, Cleveland Heights, Ohio

Application November 25, 1933, Serial No. 699,757

2 Claims. (Cl. 220—39)

This invention relates to a container, more particularly to the closing means therefor. My improved closing means is adaptable for use in connection with bung rings, including pressed-in types of rings, and lends itself for use where cap seals are employed, since the upper surfaces of the closing means lie substantially flush with the exposed end of the ring or container wall associated therewith.

10 One object of the invention is to construct a flush type of closing plug having its body recessed or cut away in a manner that provides integral related members, the sides and ends of which serve as abutments and walls utilizable for turning the plug and the upper surfaces of which form a base or backing for a cap.

Another object of the invention is to provide an improved plug, for closing an opening, formed with a recessed body portion, the side walls of the 20 recess being so shaped that a plurality of related portions are provided, whereby a standard type of tool or various other devices may be used to seat or unseat the plug.

Another object of the invention is to provide an improved flush type of closing plug having a recessed body portion shaped to provide, with a minimum amount of metal, related walls serving as a backing for seal caps and abutments for tools and other devices.

30 Another object of the invention is to construct an improved closure means comprising (a) a plug having tool engaging elements and a vent and constructed to fit substantially flush with its receiving member and (b) a closing device for said vent having tool engaging elements and constructed to fit substantially flush with the bottom of said plug.

Other objects of the invention will be apparent to those skilled in the art to which my invention relates from the following description taken in connection with the accompanying drawing, wherein

Fig. 1 is a fragmentary plan view of a container having an opening therein and a closure, embodying my invention, mounted in the opening and a sealing cap in position, a portion of the cap being broken away.

Fig. 2 is a section on the line 2—2 of Fig. 1, enlarged (the cap being omitted).

50 Fig. 3 is a view similar to Fig. 2, but showing a sealing cap in position.

Fig. 4 is a view similar to Fig. 1, but showing another embodiment of the invention.

55 Fig. 5 is a section on the line 5—5 of Fig. 4.

Fig. 6 is a view similar to Fig. 1, but showing a different embodiment of the invention.

In the drawing, 1 indicates a container having a side wall 2 and heads or end walls, only one of which is shown at 3, connected to the side wall 2 by a double seam. 4. In the illustrated form of construction the wall 3 is formed with an opening in which is mounted in any well known manner, a bung ring 5. The construction of the ring 5 is preferably similar to the ring disclosed in Letters Patent No. 1,929,412, dated October 10, 1933, and granted to me, for which reason no claim is made thereto herein. In practice it is customary to provide the container with two or more openings, for filling, venting, emptying and/or dispensing. As the closures for these openings may be and preferably are similar, only one opening is shown. As shown the ring 5 is internally threaded at 5a to receive a closure indicated as an entirety at 6. Referring to Figs. 1 and 2, the closure comprises a base 6' and an annular upstanding side wall 7 threaded externally to engage the threads 5a. Within the side wall 7 and preferably formed integrally therewith and the base 6 I provide a plurality of inwardly projecting, uniformly spaced members 8, having flat inner end walls or faces 8'. The upper surfaces of the members 8 are preferably disposed in the plane of the upper end of the side wall 7 and the side walls 8a of each member are preferably parallel to a radius of the member, for a purpose later set forth. As shown, the inner end faces 8' of the members 8 are disposed in a predetermined relation. For example, where two members 8 are provided, their end faces are in opposed or diametrical relation for engagement by a tool A, as shown in Fig. 6; when four members 8 are provided, each face 8' is in opposed or diametrical relation to one of the remaining faces 8', as shown in Fig. 1.

In the construction and arrangement above set forth, the members 8 form between them and the wall 7 diametrically arranged recesses 9 which merge with the space or area within the members 8, so that various devices, other than the usual wrench A may be inserted in two of the recesses 9 and intermediate space and engaged with two oppositely related corners 8x of the members 8 to screw in or out the closure 6. The width of each end wall 8' is somewhat less than the width of each face of the wrench, so that, while the wrench faces will be effective to screw in or out the closure 6, the adjacent corners 8x of adjoining members may be spaced from each other a considerable distance.

It will thus be seen that a minimum amount of metal is required to form the closure.

By making the upper surfaces of the members 8 flush with or in the plane of the upper end of the wall 7, such surfaces form a support or backing for the body portion of a sealing cap 20. As each member 8 is equal in width to its end face 8' and its side walls extend parallelly, it will be seen that a relatively large area occupied by the closure 6 is utilized as a backing or support for the body portion of the sealing cap 10.

The plug 6 may be used in any type of ring and with the ring mounted uprightly (see Fig. 5) or inverted, as shown in Figs. 1, 2, 3 and 6.

15 The closure 6 is provided with an annular recess 11 adjacent its upper end to receive a gasket 11a. By preference, the uppermost thread 5a in the ring opening is cut away and the upper end of the closure is provided with a shoulder 12 (being an extension of the upper wall of the recess 11), which is arranged to engage the gasket 11a and compress it, when the closure is tightened.

Where the plug is provided with a vent, I provide the bottom wall 6' with a depending integral neck 13, which is internally threaded at 14 for a closure 15. The closure 15 is similar in construction to the closure 6, that is, it is provided with a bottom wall, an externally threaded side wall adapted to be screwed into and out of the neck 13, and abutment members (similar to the members 8) integral with the bottom wall and side wall and extending inwardly from the latter for co-operative relation; also, that a gasket preferably formed of rubber, is provided to seal the opening through the neck 13. In this arrangement, (a) the abutment members lie flush with the top surface of the wall 6' between the members 8 and (b) a standard tool or other devices 40 may be used, as above set forth, to tighten or loosen the closure 15.

The closures herein disclosed may be die-cast or otherwise formed to provide the recessed body having the related walls 8.

45 It will be noted that in the combination closure shown in Figs. 4 and 5, the construction of the plug 6 permits ready access to the closure device 15.

50 In the herein disclosed construction, the plug 6 may be suitably sealed. For this purpose each member 8 is formed with a through opening 16,

whereby a wire 17 or the like may be threaded through it and an opening in a tab 18, which is spot welded to an adjacent portion of the container wall, the ends of the wire being connected by a lead sealing slug 19. The above described sealing arrangement is shown in Figs. 1, 4 and 6. Where the bung ring is mounted in an inverted position as shown in Figs. 2 and 3, which provides an annular shoulder adjacent the upper end of the ring or the construction of ring mounting 10 provides such a shoulder, a sealing cap 20 may be used as shown in Fig. 3. That either form may be adapted, is fully shown in Fig. 1.

To those skilled in the art to which my invention relates, many changes in construction and widely differing embodiments and applications of the invention will suggest themselves without departing from the spirit and scope thereof. My disclosures herein are purely illustrative and are not intended to be in any sense limiting.

What I claim is:

1. A hollow plug having a relatively thin, exteriorly threaded rim or flange provided with a sufficient number of radially inwardly extending lugs terminating in opposed relatively wide flat active faces to form a socket for a tool, the top faces of said lugs being substantially flush with and extending inwardly from the top of said rim and distributed about the central portion of the plug to form a substantial support 30 for the inner portion of a sealing cap, said lugs being separated from each other to admit a substantially flat device arranged to operate laterally thereon as a turning tool.

2. A hollow plug having a relatively thin, exteriorly threaded rim or flange provided with a plurality of radially inwardly extending lugs each having side walls parallel to a radius of the plug and terminating in a substantially flat relatively wide face and parallel to the face of the opposed lug, said faces cooperating to form a socket for a tool, the top faces of said lugs being substantially flush with and extending inwardly from the top of said rim and distributed about the central portion of the plug to form a substantial support 45 for the inner portions of a sealing cap, said lugs being uniformly separated from each other to admit between them a substantially flat device arranged to operate laterally thereon as a turning tool.

HENRY M. DILLHOEFER.
